UNITED STATES PATENT OFFICE.

JOHN PATTEN, OF BALTIMORE, MARYLAND.

FEED-WATER PURIFIER.

No. 918,586.

Specification of Letters Patent. Patented April 20, 1909.

Application filed August 19, 1908. Serial No. 449,301.

To all whom it may concern:

Be it known that I, JOHN PATTEN, a resident of Baltimore, in the State of Maryland, have invented certain new and useful 5 Improvements in Feed-Water Purifiers; and I do hereby declare the following to be a full, clear, and exact description of the invention, such as will enable others skilled in the art to which it appertains to make

10 and use the same.

My invention relates to improvements in feed water purifiers for steam boilers, and more particularly to that type in which live steam from the boiler is employed in the 15 purifier for effecting the separation of such impurities from the water as would result in the formation of scale.

One object of my present invention is to so construct a feed water purifier that it can 20 be readily cleaned and the artificial stone formed therein easily removed.

A further object is to construct a feed water purifier in such manner that the choking of the mouth of the feed pipe where 25 it communicates with the cylinder of the purifier and where said pipe communicates with the boiler, by the accumulation of materials which would form scale, will be obviated.

30 With these objects in view the invention consists in certain novel features of construction and combinations of parts as will be hereinafter set forth and pointed out in the claims.

35 In the accompanying drawings, Figure 1 is a vertical cross section of a feed water purifier embodying my improvements. Fig. 2 is a horizontal cross section of the same, and Fig. 3 is a partial sectional view showing 40 the means (in elevation) for withdrawing the chain from the purifier cylinder.

1 represents a cylinder or tank provided near its lower end with brackets 2 by means of which the device is supported upon posts 45 or pedestals 3. The cylinder 1 is provided with a conical or hopper-bottom 4 normally closed at its lower end by means of a cap 5 removably secured in place. A discharge pipe 6 communicates through the cap 5 with the bottom of the cylinder, and this pipe is provided with a normally closed blow-off valve 7.

A cover 8 normally closes the top of the cylinder 1 and is removably held in place 55 by suitable bolts 9—10. A crane 11 is revolvably mounted in a socket in one of the

brackets 2 and guided by perforated lug or projection 12 at the top of the cylinder. The upper member of this crane projects partially over the cover 8 and is connected 60 with the center of the latter. Means are thus provided for swinging the cover from the top of the cylinder and supporting the same when the interior of the cylinder is to be cleaned.

65 The cylinder 1 is divided by a vertical partition 13 into two chambers 14 and 15. The upper end of the partition 13 terminates an appreciable distance below the upper end of the cylinder and the lower end 70 of said partition terminates at a point approximately coincident with the juncture of the body of the cylinder with the hopper-bottom thereof. The lower end of the chamber 14 is tightly closed at a point some distance above the lower end of the partition 13, by means of a horizontal partition 16. The chamber 15 is provided with a perforated bottom or partition 17 preferably located in a plane somewhat above the bottom 16 of the chamber 14. The bottom or partition 17 may comprise two members, the upper member 18 being perforated and placed upon the lower member so as to cover an opening 19 of considerable size. 75 The said upper member 18 of the partition 17 may be removable so that access entirely through the cylinder may be afforded to facilitates thorough cleansing of the interior 80 of the apparatus.

85 A chain 20 is located within the cylinder 1 and made to occupy both chambers 14—15 thereof,—said chain resting upon the bottoms 16—17 of said chambers and being made also to occupy more or less of the 90 space above the vertical partition 13.

95 A water inlet pipe 21 communicates with the chamber 14, near the lower end thereof, and a water outlet pipe 22 communicates with the cylinder 1, below the bottom 16 of 100 chamber 14, and above the lower end of the vertical partition 13. A steam pipe 23 from the dome of the boiler which my improved purifier is to supply with water, communicates with the cylinder 1 at a point below 105 the bottom 17 of chamber 15 and above the plane of the water outlet pipe 22 and the lower end of the vertical partition 13. A pipe 24 communicates with the upper end of 110 the cylinder 1 for the escape of steam and gases liberated from the water and commingling with such steam.

Water from a suitable feed pump enters, by way of pipe 21 into the chamber 14 and after this chamber shall have become filled to the height of the partition 13, the water 5 will trickle or percolate through the chain, 20 and at the same time be heated by live steam entering through the pipe 23. This live steam passes upwardly through the perforated bottom 17 of chamber 15 and 10 through the chain 20, coming into direct contact with the water and heating the same to boiler temperature. Under these conditions the free carbonic acid is volatilized and the soluble bi-carbonates of such minerals as lime, magnesia, iron, etc., are decomposed and converted into insoluble mono-carbonates which adhere to the surface of the chain links and to scale which may have previously been formed on the latter, while 15 the purified water will finally reach that portion of the cylinder below the partitions 16 and 17. The organic matter in the water is also decomposed and breaks up into volatile compounds which pass off with the steam 20 through the pipe 24. The character of the gases generated will of course depend upon the nature of the organic matter in the water. Thus albuminous substances mostly break up into carbonic acid and ammonia, 25 while fatty matter, such as the glycerids of the fatty acids, break up mostly into organic acids, such as tannic acid, acetic acid, oleic acid, stearic acid, etc. Calcium sulfate that may be in the water is rendered insoluble 30 by exposure to the heat of the live steam and accumulates in the form of artificial weak stone on the chain. The water which percolates through the chain may not be entirely deprived of the minerals thrown out 35 of solution by the heat and elimination of the gas, and therefore the bottom of the cylinder is utilized as a settling tank. The water which passes through the perforated bottom 17 of the chamber 15 becomes de- 40 posited in this settling tank and, there being no vaporization, the sediment settles and separates from the water. The water, after descending to the lower end of the partition 13, then ascends on the other side of this 45 partition and passes off through the pipe 22 to the boiler. After the sediment has accumulated to some extent in the bottom of the tank, the valve 7 is opened and such sediment is blown out. 50

55 One of the difficulties in steam boilers and live steam purifiers is the choking of the mouth of the feed pipe where it enters the boiler or purifier. The sudden elimination of the gases and the heating of the water 60 forms an undue amount of sediment in and around the mouth of the pipe. This sediment is of the nature of boiler scale and so chokes the end of the pipe as to render frequent cleaning necessary. This difficulty is 65 avoided in my purifier by the provision of

the chamber 14 having a water tight bottom 16. The water ascends through this compartment and is heated from the top, the heat descending slowly, so that the mouth of the feed pipe 21 and the immediate vicinity thereof is left comparatively cool, and therefore little scale will accumulate to interfere with the water. After the water has passed over the top of the partition 13 however, it comes into direct contact with the 70 live steam from the boiler and is heated quickly and caused to deposit its scale on the links of the chain. After one section of the links in chamber 15 has become filled with artificial stone or scale, the water will 75 be deflected to neighboring links and will continue to change its course until the spaces between the links of the chain shall be sufficiently filled with scale to prevent the free flow of water. It will then be necessary to 80 clean the purifier. This is accomplished by removing the head 8 of cylinder 1 and then withdrawing the chain 20, at the same time breaking the artificial stone or scale into 85 small fragments. 90

The chain 20 can be conveniently withdrawn from the cylinder by means of a windlass 25—the chain passing from the cylinder over a pulley 26 and then downwardly so as to be engaged or to wind on the 95 windlass, said chain being finally deposited upon the ground. The windlass may be provided with a gear wheel 27 to be engaged by a pinion 28 and the latter may be operated by means of a crank 29. Any artificial 100 stone or scale which may still adhere to the chain after it has been removed from the cylinder may be dislodged from the chain in any suitable manner and in some instances it may be found desirable to place the chain 105 in a furnace for disintegrating the scale.

Various slight changes might be made in the details of construction of my invention without departing from the spirit thereof or limiting the scope and hence I do not 110 wish to restrict myself to the precise details herein set forth.

Having fully described my invention what I claim as new and desire to secure by Letters-Patent, is:—

1. In a feed water purifier of the character described, the combination with a tank provided with a water inlet and a water outlet, of a removable chain located within the tank between the water inlet and the water 120 outlet, a live steam pipe communicating with said cylinder thereby exposing the surface of said chain and scale deposited thereon to live steam, and an escape pipe from said tank to discharge the gases generated there- 125 in mixed with steam as described.

2. In a feed water purifier, the combination with a tank provided with an inlet and an outlet for water and also provided with an inlet and an outlet for steam, of a flexible 130

- device adapted to receive scale deposit, removably disposed within said tank between the steam inlet and outlet.
3. In a feed water purifier, the combination with a tank, of a partition dividing said tank into two chambers, a tight bottom for one of said chambers, a perforated bottom for the other chamber, a water inlet pipe communicating with the chamber having the 10 tight bottom, a water outlet pipe communicating with the tank below the chamber having the tight bottom, a live steam pipe communicating with the tank, and a gas and steam escape pipe communicating with the tank.
4. In a feed water purifier, the combination with a tank, of a partition dividing said tank into two chambers, a tight bottom for one of said chambers, a perforated bottom 20 for the other chamber, a water inlet pipe communicating with the chamber having the tight bottom, a water outlet pipe communicating with the tank below the chamber having the tight bottom, a live steam pipe communicating with the tank in proximity to the chamber having the perforated bottom, a gas and steam escape pipe communicating with the tank and flexible scale collecting means located within the 25 tank above the plane of the live steam inlet.
5. In a feed water purifier, the combination with a tank and a horizontal perforated partition therein, of a flexible scale collecting device removably disposed over said partition, means for discharging water downwardly through said flexible device, means for simultaneously passing steam through said flexible device, an escape pipe communicating with the tank, and a water discharge pipe also communicating with said 30 tank.
6. In a feed water purifier, the combination with a tank and a horizontal perforated partition therein, of a scale collecting device consisting of a series of connected links, 45 removably disposed over said perforated partition, means for passing water downwardly through said connected series of links, means for simultaneously passing live steam through said connected series of links, an escape pipe communicating with the tank, and a water outlet pipe communicating with the tank below the plane of said connected 50 series of links.
7. In a feed water purifier, the combination with a tank, of a vertical partition therein terminating at its respective ends appreciable distances from the respective 55 ends of the tank, a tight bottom for one of the chambers formed by said partition and located at an appreciable distance above the lower end of said partition, a perforated bottom for the other chamber formed by said partition and also located at appreciable distance above the lower end of said partition, a flexible scale collecting device removably supported in said chambers over the bottoms thereof, a water inlet pipe communicating with the lower portion of the chamber having the tight bottom, a water outlet pipe communicating with the tank below said tight bottom and above the lower end of the vertical partition, a live steam inlet pipe communicating with the tank in proximity to the other chamber, and an escape pipe communicating with the tank.
8. In a feed water purifier, the combination with a tank provided in its bottom with a settling chamber, and a blow off valve communicating with said settling chamber, of a flexible scale collecting device in the upper portion of the tank, means for passing water downwardly through said scale collecting device, means for simultaneously passing live steam upwardly through said scale collecting device, an escape pipe communicating with the tank, and a water outlet pipe communicating with the tank in a plane below the scale collecting device.
9. In a feed water purifier, the combination with a tank, a removable cover thereof and a perforated partition disposed horizontally within said tank, of a scale collecting chain located upon said partition, and a windlass for removing said chain from the cylinder.
10. In a feed water purifier, the combination with a tank and a horizontal perforated partition therein, of a removable cover for said cylinder, a crane for supporting said cover when removed, a scale collecting chain removably disposed in said tank over the perforated partition; means for passing water downwardly through said chain, means for passing live steam through said chain, an escape pipe communicating with the tank, a water outlet pipe communicating with the tank below the plane of the scale collecting chain, and means for removing the scale collecting chain from the cylinder.

In testimony whereof, I have signed this specification in the presence of two subscribing witnesses.
